UNITED STATES PATENT OFFICE

161,352

GAME BOARD

Gerard Madieu, Monaco, Monaco

Application July 24, 1947, Serial No. 140,494
In France July 12, 1946

Section 1, Public Law 690, August 8, 1946

Term of patent 14 years

(Cl. D34—5)

To all whom it may concern:

Be it known that I, Gerard Madieu, citizen of the French Republic, residing at Monaco, Principality of Monaco, 55 Boulevard du Jardin Exotique, have invented a new, original, and ornamental Design for a Game Board of which the following is a specification, reference being had to the accompanying drawing, forming part thereof.

The single figure is a perspective view of the game board, showing my design.

What is claimed is:

The ornamental design for a game board, as shown.

GERARD MADIEU.
